BOLSTER BLOCK

Cyril J. Bath, Cleveland, Ohio, assignor to The Cyril Bath Company, a corporation of Ohio.

Application October 11, 1947, Serial No. 779,308

4 Claims. (Cl. 153—21)

1

This invention relates to an improved bolster block for a press brake and to the method of making the same.

Heretofore, in connection with press brakes it has been a common practice to interpose between either die and the associated leaf of the press brake, a bolster block which is to be anchored to the associated leaf and in turn adjustably supports the die.

Usually such bolsters are adjustable by means of wedges interposed between the main body of the bolster and the anvil or die supporting plate.

Furthermore, due to the heavy impacts and stresses to which they are subjected, they are made of cold rolled steel or equally heavy and compact metal. The various parts such as the body and wedges are machined to shape from solid steel stock of rectilinear cross section or roughly rolled stock which must be machined heavily to provide the desired shapes.

I have discovered that extruded aluminum, or alloy which is predominantly aluminum, has sufficient tensile and compressive strengths relative to its volume to render it desirable for making an adjustable bolster block of practical size and suitable strength for use in press brakes wherein steel bolster blocks have been considered necessary, heretofore.

Furthermore, I have discovered that the aluminum, or alloy, may be extruded into elongated sections which conform sufficiently closely in cross sectional shape and dimensions to the cross sectional shapes and dimensions required for the main body and wedges of the bolster block that both the body and the wedges can be formed as extruded sections and require at most only a light surface finish of their interfitting surfaces to condition them for final assembly into an accurate and efficient bolster block.

The extruded aluminum not only is much stronger in relation to its weight than the same metal when cast or rolled, but apparently the grain structure is better adapted for my purposes, the extruded section being less subject to warping both during manufacture and use.

Again, the presently used bolster blocks being very heavy, in a press brake of any size the installation and removal of the block are arduous tasks and usually require more than one workman, whereas, for a comparable size press brake, the bolster block of the present invention is very light and may be installed readily by a single workman.

It has the advantages, therefore, of economy in manufacture, ease of installation, and light

2

weight, coupled with qualities of durability at least as good as the steel bolster blocks heretofore used.

Other advantages of the present invention will become apparent from the following description wherein reference is made to the drawings, in which:

Fig. 1 is a front elevation of a bolster block embodying the principles of the present invention;

Fig. 2 is an enlarged cross sectional view taken on line 2—2 of Fig. 1; and

Figs. 3 and 4 are a top plan view and left end elevation, respectively, of one of the wedges of the bolster block of Fig. 1;

Referring to the drawings, the bolster block shown is one for use with the bottom leaf of a brake press and comprises an elongated body 1 of generally channel shaped cross section, having a longitudinal channel 2 opening through the top face and coextensive longitudinally with the body 1.

The channel has a wedge engaging bottom wall 3 which is inclined transversely of the body at the desired angle, for example, about 10° to the horizontal.

On the bottom face of the body is an integral longitudinal anchor rib 4 which is adapted to be accommodated in and fit the usual complementary upwardly open channel in the bottom leaf of the press brake so as to constrain the bolster from displacement transversely of the length of the leaf.

Within the channel 2 is an anvil or die supporting member 4 which may be of the usual cold rolled steel and which fits between the side walls of the channel with operating clearance. The member 4 is preferably of generally rectilinear cross section and is provided with the usual channel 5 which accommodates a portion of the die in the usual manner.

The well known fastening devices for connecting a bolster to the leaf and a die to the anvil are provided and are omitted from the illustration as they form no part of the present invention.

Interposed between the horizontal bottom of the anvil 4 and the inclined bottom wall 3 are a plurality of wedges 6 which are individually movable transversely of the body for adjusting the anvil and thereby the die which it supports.

The wedges have horizontal top walls complementary to the undersurface of the anvil and inclined bottom wall complementary to the wall 3.

The wedges are identical with each other and are of less width transversely of the body 1 than

is the channel 2 so as to afford a considerable range of movement transversely of the channel.

Each wedge is provided with a vertical notch 7 which extends entirely therethrough from top to bottom at the thick edge of the wedge. The notch is preferably T-shape in plan and opens through the thick edge of the wedge, as illustrated, so as to accommodate the head 8 and neck 9 of a suitable socket end adjusting screw 10.

The adjusting screws 10 are arranged one to each wedge and are threadably engaged in the threaded bores 11 respectively, each of which extends from the channel through the forward wall of the body 1.

The wedges usually are of greater dimension longitudinally of the channel 2 than transversely thereof and arranged in edge to edge relationship with only operating clearance so as to form a supporting surface which is substantially uninterrupted for the full length of the body 1.

The body 1 is a length of extruded aluminum section of which the cross section, as extruded, is substantially the same in shape and dimension as the cross section of the finished body 1. Very slight machining or surface finishing of certain surface portions which may have slight superficial irregularities which occur occasionally in extruded metal shapes may be required in some very occasional instances, but generally such instances are exceptions and no machining of surfaces is necessary.

The same is true of the wedges which are merely lengths cut off of an elongated extruded aluminum section of the same cross sectional shape and dimensions, as extruded, as the wedges.

The only machining operations required on both the body 1 and the wedges 6 are not surface machining but are limited to the boring and tapping of the bores 11 in the body 1 and the cutting of the slots 7 in the wedges 6. The sawed edges of the lengths forming the wedges are sufficiently accurate as cut so that no surface finishing thereof is required. Likewise, the other surfaces of the wedges either require no finishing or, at most, in some rare instances, the slight finishing mentioned to remove slight superficial irregularities.

Starting therefore, with the two extruded sections, it is apparent that a light and durable adjustable bolster block can be produced efficiently and at a very low cost.

Having thus described my invention, I claim:

1. A bolster block adapted to be interposed between a die of a press brake and its associated leaf and comprising a body which is an elongated extruded metal section in substantially the cross-sectional shape in which extruded and which is predominately aluminum and which is of substantially uniform cross section and has a longitudinally extending channel opening in one of its faces, an elongated vertically movable die sup-

porting member fitting in the channel so as to be constrained thereby from movement transversely relative to the body, a plurality of wedges interposed between and bearing against the underside 8 of the member and the inside bottom wall of the channel and movable transversely of the body for adjusting the member vertically, said wedges being arranged in a row in substantially abutting relation with each other endwise of the row for substantially their full width transversely of the row and said row extending substantially the entire length of the die supporting member, screw means mounted in said body for movement transversely thereof and operatively connected to the wedges, respectively, for moving the wedges, respectively, transversely to different adjusted positions, and anchor means in the form of an integral elongated rib on the body adapted to interconnect the body and the associated leaf to constrain the body from movement transversely.

2. A bolster according to claim 1 wherein the inner side wall surfaces of the channel are substantially upright and the inside bottom wall of the channel is unidirectionally inclined transversely of the body for substantially the full width of the channel.

3. A bolster according to claim 1 wherein the wedges have flat surfaces fitting against the underside of the member and inclined surfaces fitting against the said inclined bottom wall.

4. A bolster according to claim 3 wherein the wedges are a plurality of relatively short severed lengths of an elongated extruded section of metal which is predominantly aluminum and which, as extruded, has the same cross section, laterally of the body, as the wedges.
